P. GRASSMANN

LOUD SPEAKER FOR WIRELESS TELEPHONY AND OTHER PURPOSES

Filed March 20, 1925

Inventor
P. Grassmann
By Marks & Clark

UNITED STATES PATENT OFFICE.

PETER GRASSMANN, OF BERLIN, GERMANY.

LOUD SPEAKER FOR WIRELESS TELEPHONY AND OTHER PURPOSES.

Application filed March 20, 1925, Serial No. 17,123, and in Germany February 9, 1925.

This invention relates to improvements in loud speakers comprising a sound box mounted on a telephone casing and of the kind in which an electro-magnetically operated pivoted armature mounted in the telephone casing is connected to a vibrating diaphragm mounted in the sound box through the intermediary of a controlling pivoted member and in which the latter is linked to the pivoted armature at a point which is eccentric with respect to the centre of the armature and the centre of the diaphragm.

Two forms of construction according to the present invention are illustrated by way of example in the accompanying drawings, in which:—

Figures 1 and 2 illustrate in sectional elevation and plan view respectively one form of construction, the vibrating diaphragm in the upper part of the sound box being removed in Figure 2;

Figure 3 illustrates in sectional elevation the second form of construction.

Referring to the form of construction illustrated in Figures 1 and 2, 1 is the telephone casing and 2 the sound box which is mounted coaxially therewith. The abutting surfaces of the two casings are ground or turned, so that a rigid coaxial connection can be ensured between them by means of fixing screws in a well known manner. The magnetic system of the telephone may consist of the usual permanent magnets 3 of horse-shoe shape, having pole shoes provided with coils 4. The pole surfaces 5 and the end surface of the casing 1 are ground simultaneously thereby ensuring that all these surfaces shall lie in one and

the same plane. The armature 6 is arranged at a short distance from the pole surfaces, and it consists of a lever which is arranged to oscillate for instance about an axle 7 surrounded by a helical spring 8 and is provided with a flat flexible extension 9 which rests upon an adjusting pin 9. The lower surface of the armature 6 is also ground so as to form a flat surface which will be parallel to the pole surfaces, its

distance from the latter being adjusted by means of insertions 10. The displacement of the pin 9 required for the fine regulation is effected by means of an eccentric shaft 11 provided with a controlling knob 12 and passing transversely through the hole 13 in which the adjusting pin 9 is guided, the

head 14 of the latter pressing against the eccentric part of the shaft under the control of a spring 15. This form of construction also prevents the shaft 11 from being withdrawn axially. The turning of the knob 12 causes the pin 9 to be shifted in its axial direction, thereby regulating the sensitiveness of the armature.

The armature 6 carries a support or bearing 16 arranged eccentrically with respect to the centre of the armature, the controlling member 18 mounted in the sound box being rotatably secured to the said bearing, and the latter lying between the rocking point 17 and the arm of the controlling member which is connected to the diaphragm. The pivot in the support 16 may be constituted by a screw or screws screwed in laterally, so that the sound box and the telephone casing may be manufactured entirely separately and be secured together subsequently, the connection between the armature 6 and the controlling member 18 being effected simply by screwing in the pivot screw or screws through suitable holes formed in the side wall of the sound box.

A particular advantage of the arrangement according to the present invention consists in the production of a double multiplying effect; the one is determined by the ratio of the distance between the middle of the armature and its axis, to the distance between the middle of the armature and the bearing 16 and the other one by the ratio of the distance between the bearing 16 and the rocking point 17 of the controlling lever to the distance between the support 16 and the centre of the diaphragm 19.

Referring to the arrangement illustrated in Figure 3 the same differs from that described with reference to Figures 1 and 2 by the telephone casing being constructed in two parts 1, 1', the armature 6 being arranged so as to oscillate between two magnets 4, 4' which are energized in such a manner that they shall be of opposite polarities, and the flat flexible arm 8 at the end of the armature being secured to the adjusting pin 9. The sound box 2 is mounted coaxially with the two parts 1, 1' of the telephone casing whilst the support 16' of the controlling member 18 projects through the casing 1'.

It is to be understood that in both forms of construction the aperture 20 provided in the sound box is intended to effect communi-

cation with the usual trumpet or its equivalent, which has not been illustrated in the drawing as it does not form part of the present invention.

5. What I claim is:—

1. A loud speaker comprising in combination a sound box having a vibrating diaphragm mounted therein, a telephone casing having an electrically controlled magnet and an armature pivotally mounted therein, a wall separating the sound box from the telephone casing, a controlling pivoted member in the sound box connected to the centre of the diaphragm and a connecting member 10 between the said controlling member and the armature, the points of connection of the connecting member with the said controlling member and with the armature respectively being eccentric with respect to the centre thereof and the controlling member passing through the wall separating the sound box from the telephone casing as set forth.
2. A loud speaker comprising in combination a sound box having a vibrating diaphragm mounted therein, a telephone casing having an electrically controlled magnet and an armature constructed in the form of a lever capable of oscillating about a point 15 lying on the edge of the telephone casing, a controlling member pivoted in the sound box and connected to the centre of the diaphragm and a support on the armature which lies eccentrically with respect to the centre of the telephone casing and supports the controlling member between the rocking point 20 of the latter and the centre of the diaphragm, as set forth.

3. A loud speaker comprising in combination a sound box having a vibrating diaphragm mounted therein, a telephone casing having an electrically controlled magnet and an armature pivotally mounted therein, a controlling pivoted member in the sound box 40 connected to the centre of the diaphragm, a connecting member between the said controlling member and the armature, the points of connection of the connecting member with the said controlling member and with the armature respectively being eccentric with respect to the centres thereof, an adjustable pin in the telephone casing and an extension on the armature which extension is supported by the said adjustable pin, as set forth. 45

4. A loud speaker as claimed in claim 3 and in which the extension of the armature is secured to the adjustable pin as set forth. 50

5. A loud speaker comprising in combination a two part telephone casing, an electrically controlled magnet in each part thereof, an armature between the said two parts, a sound box with vibrating diaphragm mounted on the two-part telephone casing coaxially therewith, a controlling member within the sound box connected to the centre of the diaphragm, and a connecting member between the said controlling member and the armature, the points of connection of the connecting member with the armature and the controlling member respectively being eccentric with respect to the centres thereof, as set forth. 60 65 70

In testimony whereof I have signed my name to this specification.

PETER GRASSMANN.
